SCARIFIER TOOTH

Carroll M. Walker, Los Angeles, Calif., assignor to
 Mills Alloys, Inc., Los Angeles, Calif., a corporation of Delaware

Application November 7, 1932, Serial No. 641,584

7 Claims. (Cl. 262—33)

This invention relates to scarifier teeth. Such teeth in general usually comprise a narrow body with an advancing or leading edge, for engagement with the earth's surface, for scarifying or loosening it. Since considerable friction is developed between the active portion of the teeth and the earth through which it is drawn, these teeth are subjected to considerable wear.

It has been proposed to reduce the extent of the wear, and thereby to lengthen the life of the teeth, by the addition of a hard facing compound integrally fused to the leading edge of the tooth. Such a compound, for example, may be tungsten carbide particles in an iron or other metallic matrix or binder, which compound is integrally fused to the body of the tooth, as by welding.

It is one of the objects of this invention to improve in general, scarifier teeth of this character; and especially by ensuring against deleterious effects of shocks imparted to the leading edge of the tube.

More specifically, if a thick layer of such a tungsten carbide compound be applied to the leading edge, this thick layer, even if it be embedded in a groove along the leading edge, has brittle characteristics; and shocks imparted to the tooth by being dragged through the material to be scarified may readily crack or break the layer of compound. This may occur in spite of the fact that an integral fusion has taken place between the compound and the body of the tooth.

This disadvantage is obviated by the aid of the present invention. By building up the hard wearing edge in laminations or layers alternating with layers of metal having good shock resisting characteristics, the shocks to which the tooth may be exposed are quite evenly distributed throughout these alternate layers, and they can withstand the blows and shocks without material danger of breaking or cracking.

It is still another object of this invention to make it possible to control the maximum bluntness of the tooth; more specifically, by reducing the depth of the active portion of the tooth; as well as the area thereof, as by the aid of a deep groove in the back of the tooth.

My invention possesses many other advantages, and has other objects which may be made more easily apparent from a consideration of one embodiment of my invention. For this purpose I have shown a form in the drawing accompanying and forming part of the present specification. I shall now proceed to describe this form in detail, which illustrates the general principles of my invention; but it is to be understood that this de-

tailed description is not to be taken in a limiting sense, since the scope of my invention is best defined by the appended claims.

Referring to the drawing:

Figure 1 is a side elevation of a scarifier tooth embodying the invention, but partly broken away in order to reduce the size of the figure;

Fig. 2 is a front elevation thereof;

Fig. 3 is a cross sectional view on an enlarged scale, taken along plane 3—3 of Fig. 2; and

Fig. 4 is an enlarged detail section through the leading edge of the tooth.

The tooth in general can have a longitudinal body 1 of appropriate length and of general rectangular configuration. The lower edge of the body 1 is shown as tapered as at 2, to provide a pointed leading edge 5. Furthermore, the active portion of the tooth is cut away to a plane 3 to reduce the area of the cutting point, a deep groove 4 is provided in the back thereof. The leading face of the tooth is preferably sharply beveled, as shown, to assist in the scarifying action.

Preferably, the body is made from shock resisting metal. Such metal may be mild steel or chrome vanadium steel, or the like. It is apparent that as the tip 5 wears, the maximum area of contact between the worn tip and the ground is governed by the area of the cross section of the tooth. This area is reduced by the slot 4, as well as by cutting the back of the tooth away to the plane 3. Accordingly, the tooth remains sufficiently sharp to be continued in service until it wears down to the unreduced section of the body 1.

Preferably, the leading edge of the tooth is overlaid with hard wearing material. To accommodate the hard wearing material, a groove 6 extending longitudinally of the leading edge can be provided in the tooth. This groove is preferably formed with a round or substantially round bottom. This groove can be appropriately formed by a machining operation, but other ways for providing the groove can be utilized.

The hard facing material fills the groove and extends over substantially the entire area of the leading edge of the tooth. One of the most desirable forms of hard wearing material is a compound of tungsten carbide granules and a binder of iron, iron alloy, nickel, cobalt, or other metals of the iron group. Although a wide range in size in tungsten carbide granules can be utilized, they are usually of the order of granules that will stay on a 30 mesh screen and that will pass through a 16 mesh screen.

100

105

110

The mechanical mixture or compound of tungsten carbide granules and the binder material is deposited in groove 6 in alternate layers 7, 8, 9, 10, and 11. Alternating between these 5 layers are layers of metal 12, 13, 14 and 15 having shock resisting characteristics, and preferably of the same material as the body 1. Such material may be mild steel or some other iron alloy.

These alternate layers 7 to 15 inclusive are 10 deposited in succession, preferably by a welding action, such as by the aid of an oxy-acetylene torch. The binder of the compound is fused by the torch, but the tungsten carbide particles are not affected thereby. Therefore, the binder holds 15 the granules firmly in place, and is integrally fused to the tooth. It has been found that a sufficient amount of binder material is secured when using 10 percent or more by weight of the total compound for the binder material.

20 After the first layer 7 is thus deposited, the shock resisting layer 12 can be deposited there-over by an ordinary welding operation; and suc-ceeding layers are formed in alternation as just described.

25 The outermost layer 11 can be extended as in-dicated in Fig. 3 to cover substantially the entire leading edge of the tooth. It is also apparent that the alternate layers of hard wearing and shock 30 resisting materials provide a structure that can withstand long wear and hard usage. In general practice, the groove 6 can be of the order of one-half inch wide and about one-half inch deep. The layers of hard wearing material, such as 7, 35 8, 9, 10 and 11 can be of the order of one-sixteenth of an inch thick; and the alternate layers 12, 13, 14 and 15 of shock resisting material can be made thinner.

I claim:

1. A scarifier tooth having a metal body, with 40 a leading edge, and alternate layers of hard wear-ing material and metal of the same general char-acteristic as the body metal, said layers being integrally fused to the leading edge, and spaced in the direction of travel of the edge.

2. A scarifier tooth having a metal body, with a leading edge, and alternate layers of a com-pound of hard particles and a metallic binder, and of shock resisting metal, said layers being integrally fused to the leading edge, and spaced in the direction of travel of the edge. 80

3. A scarifier tooth made from metal and hav-ing a longitudinal groove along its leading edge, and alternate layers of hard wearing material and shock resisting metal in said groove and in-tegrally fused to the tooth, said layers being sub-stantially coextensive with the groove and ex-tending lengthwise thereof. 85

4. A scarifier tooth made from metal and hav-ing a longitudinal groove along its leading edge, and alternate layers of a compound of hard par-ticles and a metallic binder, and of shock resist-ing metal in said groove and integrally fused to the tooth, said layers being substantially coex-tensive with the groove and extending lengthwise thereof. 90

5. A scarifier tooth having a metal body, with a leading edge, and alternate layers of a com-pound of tungsten carbide particles and a metal-lic binder, and of shock resisting metal, said lay-ers being integrally fused to the leading edge, and spaced in the direction of travel of the edge. 100

6. A scarifier tooth made from metal and hav-ing a longitudinal groove along its leading edge, and alternate layers of a compound of tungsten carbide particles and a metallic binder, and of shock resisting metal in said groove and integrally fused to the tooth, and spaced in the di-rection of travel of the edge. 105

7. A scarifier tooth made from metal and hav-ing a longitudinal groove along its leading edge, alternate layers of hard wearing material and a softer metal in said groove and integrally fused to the tooth, said layers being substantially co-extensive with the groove and extending length-110 wise thereof, and a supplemental layer of hard wearing material disposed over the groove and adjacent the edges thereof. 115
